UNITED STATES PATENT OFFICE.

KIRK S. BLANCHARD, OF BROOKLYN, NEW YORK.

BALL-COCK FOR FLUSH-TANKS OF WATER-CLOSETS.

1,114,575.

Specification of Letters Patent.

Patented Oct. 20, 1914.

Application filed October 5, 1912. Serial No. 724,167.

To all whom it may concern:

Be it known that I, KIRK S. BLANCHARD, of Brooklyn, in the county of Kings, in the State of New York, have invented new and useful Improvements in Ball-Cocks for Flush-Tanks of Water-Closets, of which the following, taken in connection with the accompanying drawings, is a full, clear, and exact description.

This invention relates to certain improvements in ball cocks for flush tanks of water closets and similar devices in which the supply of water to a tank is controlled by a float operated valve. I am aware that a great many different devices have been employed for this purpose, but my invention is restricted to that class in which the plunger valve is closed endwise with an end thrust against a seat surrounding the inlet port by means of a float and suitable connections between the float lever and valve so that the pressure of the valve against its seat is in direct opposition to the fluid pressure at the inlet port. One of the advantages of this type of valve is that it opens full instantly when the opposing pressure of the float is relieved by the flushing of the tank, the pressure of the fluid at the inlet port serving to assist the instantaneous opening of the valve. Under such conditions, the pressure of the fluid, tending to open the valve, is constant and one of the primary objects of my present invention is to assemble the float lever and its connection with the valve in such manner that a comparatively light upward pressure upon the float will produce a maximum degree of pressure upon the valve, tending to hold it to its seat against the pressure of the fluid.

Another object is to provide simple means for preventing the forcible exit of water along the valve through the open end of the valve chamber so as to permit the use of a plain metal plunger without packing.

A still further object is to limit the range of movement of the float lever to a relatively short arc in opening and closing the valve, thereby obviating the usual long travel of the float from the normal water level to the bottom of the flush tank.

Other objects and uses will be brought out in the following description.

In the drawings—Figure 1 is a longitudinal vertical sectional view, partly in elevation, of one form of my improved ball cock and a portion of the tank and water

supply pipe, the valve case being secured to the top of the tank while the supply pipe extends through the bottom of the tank and is connected to the valve case by a slip joint. 60 Fig. 2 is a similar sectional view, partly in elevation, of another form of my invention in which the valve case is secured to the top of the tank while the supply pipe leads to the valve case from the top of the tank. 65 Fig. 3 is a longitudinal vertical sectional view of a still further modified form of my invention in which the valve case is secured directly to the bottom of the tank and the link connection between the float lever and valve is disposed at a slight angle to the axis 70 of the valve both in its open and closed positions.

In Fig. 1, I have shown a valve case —1— as provided with a laterally projecting 75 bracket —2— secured by suitable fastening means, as a screw —3—, to the upper edge or top of a flush tank —A—, the main body of the valve being disposed in an upright position some distance above the bottom of 80 the tank and is provided with an open lower end for slip connection with a water supply pipe —a—, extending through the bottom of the tank and connected thereto in any suitable manner to prevent leakage. 85

The lower end of the valve case —1— is threaded externally and provided with a centrally apertured screw-cap —4— and packing —5— to prevent leakage. The supply pipe —a— passes through the central 90 aperture in the cap —4— and packing —5—, thereby permitting the valve case to be adjusted vertically along the upper end of the supply pipe —a— to conform to different heights of tanks without liability of causing 95 leakage at the joint between the valve case and supply pipe.

The upper end of the valve case is offset laterally in the opposite direction from the bracket —2— and is provided with a cylindrical valve chamber —6—, having an inlet port —7— and an outlet port —8—, the inlet port being in constant communication with the supply pipe while the outlet port is normally cut off from communication by a 100 valve, presently described, and is provided with a conduit —9— leading downwardly for directing the inflowing water into the interior of the tank. 105

A cylindrical plunger valve —10— is fitted 110 with an easy sliding fit and movable within the valve chamber —6—, but is somewhat

longer than the distance between the valve seat as —7— and outer end of the chamber so as to allow the outer end of the valve to project some distance beyond the valve case when closed. The opposite end of the valve is recessed and provided with a packing —11— of rubber, leather or other suitable material, closing with an end thrust against the valve seat —7— which surrounds the inlet port —7—.

The intermediate portion of the valve —10— is provided with an annular groove —12— located a distance from the packing end of said valve less than the distance between the valve seat —7— and inner end of the valve case or open end of the valve chamber and is movable with said valve into and out of registration with an auxiliary discharge port —13—. This auxiliary outlet leads downwardly so as to discharge into the interior of the tank and is located a distance from the valve seat —7— slightly greater than the distance between the packing end of the valve and annular groove —12— so that the auxiliary port is normally closed by the valve when the latter is closed against its seat —7—, but is open by registration with the groove —12— as soon as the valve recedes from its seat. The object of this annular groove and auxiliary port is to neutralize or relieve as far as possible the pressure of the fluids tending to follow along the valve through the open outer end of the valve chamber, which would be detrimental particularly in valves which are secured to the top of the tank as in the device just described.

The outer end of the valve, which protrudes beyond the valve case, is pivotally connected to a link —14— which, in turn, is pivotally connected to a float lever —15—, the latter being pivoted at —16— to a suitable lug —17— on the underside of the inner end of the valve case, preferably at the inner side of the auxiliary discharge opening —13—. This float lever is provided with a vertically adjustable section —16'— carrying a float —17'— which is adapted to be operated by the rise and fall of the water within the tank. This adjustment of the float supporting section —16'— relatively to the main body of the lever —15— is effected by connecting these parts by means of a clamping bolt —18— which may be loosened at will when the adjustment is required and retightened to hold the supporting section —16'— in its adjusted position.

The pivot —16— upon which the float lever —15— is adapted to rock vertically is located in a plane below and some distance from the pivotal connection between the valve —10— and link —14— toward the packing end of the valve while the main body of the lever extends from said pivot 65 across the extended axis of the valve some

distance to the opposite side of the pivotal connection between such valve and link while the pivotal connection between the lever and link is located in approximately the direct line of movement of the valve or 70 near the extended axis of such valve when the latter is closed so as to cause the float lever to exert a direct end thrust pressure upon the valve to hold the same closed when the float is sufficiently elevated by the water 75 in the tank. This disposition of the connecting link —14— between the valve and float lever also establishes a toggle lock between the link and lever to more effectively hold the valve against its seat under the buoyant 80 pressure of the water upon the float.

As previously intimated in the statement of the object of the invention, the lever and its connections with the valve are arranged so as to permit only a relatively small movement of the lever from its closed to its extreme open position and for this purpose the pivoted end of the lever is extended toward the main body of the valve case and provided on its upper side with a flat 90 abutting face —19— for contact with an opposed abutting face —19'— on the lower side of the outer end of the valve case, said abutments being disposed a short distance from the pivot —16— toward the main 95 body of the valve case and are normally operated only a slight distance when the valve is closed with just enough clearance to allow the valve to open before the abutments are brought into contact, thereby limiting the downward movement of the float irrespective of the recession of the water in the flush tank during the flushing operation.

The construction shown in Fig. 2 is very similar to that shown in Fig. 1 except that 105 the connection between the supply pipe, as —a'—, and valve case is coaxial with the valve chamber and valve and allows the ball cock to be connected to the tank without carrying the supply pipe through any 110 part of such tank.

In the ball cock shown in Fig. 3, the valve case is secured directly to and passes through the bottom of the tank to which it is connected by any suitable water tight joint, otherwise this ball cock is very similar to that shown in Figs. 1 and 2 with the single exception that the portion of the float lever as —15'— between its pivotal connections with the valve case and link is straight and that the pivotal connection between the lever and link is adapted to move slightly above and below the extended axis of the valve, but in all of these several devices, it will be observed that the pivotal connection between the float lever and valve case is below the valve and some distance from the pivotal connection between the link and valve toward the valve seat.

It will be observed that by pivoting the 130

lever —15— to the valve case some distance below the valve and then pivoting the link —14— to the lever approximately in line with the axis of the valve when such valve is closed; the pivotal connection between the lever and link may move through and above and below the extended axis of the valve with the assurance that when the valve seat and valve wears the upward movement of the float lever will always crowd the valve to its seat. This action is also due to the fact that the pivots for the lever and link on the casing and valve respectively are located at one and the same side of the pivotal connection between the link and lever and that the lever pivot is below the valve, thereby causing the pivotal connection between the lever and link to swing through an arc which intersects the extended axis of the valve at an oblique angle with the center of such arc below the valve.

What I claim is:

1. A ball cock comprising a valve case having an inlet port and separate outlet ports at different distances from the inlet port, a plunger valve coaxial with the inlet port for opening and closing the same and movable across the outlet ports, said valve having an annular channel registering with the outlet port farthest from the inlet port, a float lever pivoted to the valve case at a point some distance below the valve and beyond the farthest outlet and extended across the produced axis of the valve some distance beyond the outer end thereof, and a link

pivotedly connected to the valve and to the lever approximately in said axis, the distance between the pivots of the link being considerably less than the distance between the lever pivot and its pivotal connection 40 with the link.

2. A ball cock comprising a valve case having an inlet port and an outlet port, a plunger valve coaxial with the inlet port for opening and closing the same and movable 45 across the outlet port, a float lever pivoted to the valve case at a point some distance below the valve and extended some distance beyond the valve and across the produced axis thereof, means for limiting the downward movement of the lever, and a link pivotedly connected to said lever and to the outer end of the valve in approximately the horizontal plane of said axis, the distance between the pivotal connections of the link 50 with the valve and lever being considerably less than the distance between the pivotal connection of the link with the lever and the pivotal support of the lever, while the distance between the pivotal connection of the 55 valve with the link and the inlet port is a considerably greater distance than the distance between a vertical plane through the pivot of the lever and said inlet port.

In witness whereof I have hereunto set my 60 hand this 28th day of September 1912.

KIRK S. BLANCHARD.
